UNITED STATES PATENT OFFICE.

HANS EMIL SCHMIDT, OF BAD OLDESLOE, GERMANY.

TOOTH-CROWN FASTENING.

1,354,696.

Specification of Letters Patent.

Patented Oct. 5, 1920.

Application filed May 14, 1919. Serial No. 297,152.

To all whom it may concern:

Be it known that I, HANS EMIL SCHMIDT, citizen of Prussia, residing at Bad Oldesloe, Salinenstrasse 17, Germany, have invented 5 certain new and useful Improvements in Tooth-Crown Fastenings, of which the following is a specification.

The object of the present invention is to provide a fastening for artificial tooth 10 crowns whereby a crown may be easily connected with a root, bridge, or palate plate and readily replaced, if broken, without replacing the crown anchor or root prong.

A further object of the invention is to 15 increase the strength of the connection between the crown anchor and the root prong, bridge or palate plate.

The invention consists in providing a 20 rearwardly sloping top bearing surface on the crown and anchor for the purpose of forming a space behind the front face of the crown between the base of the latter and the bottom of the root, bridge or palate plate and in providing a casting for insertion into 25 said space for connecting the anchor with the root-prong, bridge or plate to form a coherent body.

In employing this attachment, the sockets in the root and the crown may be very 30 narrow, so that neither one nor the other is weakened by boring. Since this attachment is also intended to be used for half crowns, it can also be used for deeply carious roots. Owing to the junction, the 35 anchor produced by casting finds, in the recess sharply offset from the socket toward the back of the crown, a particularly reliable attachment which can withstand a great pressure exerted from below against 40 the back of the crown. This pressure is taken up by the side wall of the recess situated at a short distance from the back of the crown and running parallel to the socket, so that, owing to this direction of the pressure, 45 that part of the anchor, which projects into the socket is nearly completely relieved and for this reason the artificial tooth will be extraordinarily durable.

At all events, that is to say at any de- 50 sired size or shape of the root and any position of the root socket, the same construction and size of the crown socket and recess and of the anchor can be used, so that artificial crowns can be held in store together 55 with equally shaped anchors. A broken crown therefore can be easily replaced, as

a new casting can be substituted without removing the prong from the root, as is necessary in known fastenings.

In the accompanying drawing:

Figure 1 is a vertical section of an artificial tooth crown embodying my invention.

Fig. 2 is a similar view of the crown anchor. Fig. 3 is a vertical section of a crown attached to a root, and Figs. 4 and 5 show 65 the crown attached to a bridge and palate plate respectively.

The crown *a* having a hollow back surface is provided for attaching it to the root, bridge or palate plate with a sloping base 70 surface. The dotted line shown in Fig. 1 designates the shape of a tooth crown of known construction. The socket *b* extends up to the said sloping surface, but it is not bored, as is done in known crowns, in the 75 center or behind the center of the tooth, but in front of such center, that is to say nearer to the labial part of the crown *a* and therefore can project deeply into the crown. The socket *b* expands into a sharp offset 80 cavity toward the back of the crown, thus forming a trough shaped recess *c* extending up to the sloping surface. The back wall *d* of this recess is at right angles to the base 85 *e* of the recess and runs parallel to the socket *b*.

The anchor shown in Fig. 2 fits the socket *b* and the recess *c*, exactly and forms a tightly fitting prong *f* and a lateral shoulder *g*, filling the recess. When this anchor 90 *f*, *g* is mounted in the crown, its outer surface is flush with the bearing surface of the crown *a*.

As all the crowns carried in stock have the same socket *b* and recess *c*, they can 95 without being further prepared or operated upon be mounted on roots, bridges and the like or interchanged with already mounted crowns.

When the anchor *f*, *g* is attached to a 100 root, bridge or palate plate, there will be a space between the bearing surfaces of the crown and the root, bridge or plate, which space is widened toward the back of the crown. This space will be filled by a casting produced by the aid of a plaster cast 105 model to connect the anchor with the root pin, bridge or the palate plate to form a coherent body.

In Fig. 3 a crown is shown attached to a 110 root *h*, according to the present invention. From this figure it will be seen that, owing

to the sloping bearing surface of the crown *a*, the space between this surface and the surface of the root to be filled up is widened toward the back in such manner that 5 it is very easy to pour in the metal, which connects the root prong *i* with the anchor *f*, *g*.

From Fig. 4 it will be understood that the 10 same advantages are obtained, when a bridge *k* is to be provided with an artificial tooth the casting connects the crown anchor with the bridge directly. The same is to be said with regard to the palate plate *m* shown in Fig. 5.

15 As the wall *d* is parallel to the socket *b* and is situated at a short distance from the back of the crown, there will be two 20 supporting surfaces on the anchor *f*, *g*, which give the crown a steady hold, particularly when the pressure is exerted from below in an oblique direction against the back of the tooth, as it will happen when the biting of the lower teeth is very deep, and in the direction shown by the arrow in 25 the drawing against the back side of the upper teeth.

I claim:

1. A tooth crown fastening comprising an anchor including a pin and shoulder 30 adapted to fill up a pin socket within the

crown and a trough-shaped recess projecting in said socket, the rear wall of said recess being parallel to the socket and to said anchor, the outer surface of the anchor being flush with the base surface of the crown, 35 a mounting for the crown, and a fastening means cast between the said pin and the said mounting, the casting forming a coherent body within said anchor and said mounting.

2. An artificial tooth crown including a mounting therefor, an anchor embedded in the crown having a base bearing surface sloping downwardly toward the back of the crown and conforming to the base surface 45 of the latter, thereby forming a space between the mounting and the crown behind the front face of the latter, and a fastening piece cast in said space forming a coherent body with said anchor and mounting.

3. The combination of a crown mounting, a crown, an anchor embedded therein, and a casting interposed between the crown and mounting for connecting the latter to the anchor.

HANS EMIL SCHMIDT.
